John R. Nolan

UNITED STATES PATENT OFFICE

2,177,738

MATCH PACKET

John R. Nolan, Larchmont, N. Y., assignor to
The Diamond Match Company, New York,
N. Y., a corporation of Delaware

Application July 21, 1938, Serial No. 220,486

2 Claims. (Cl. 206—29)

This invention relates to match packets and the manufacture thereof, having reference especially to the type of book matches wherein the end of the paperboard cover remote from the match heads is constructed to present a flat friction bearing surface of substantial width, as illustrated in Letters Patent of the United States No. 2,101,111 dated December 7, 1937.

The object of the invention is to provide for such book matches a friction bearing surface of such character that the liability of the outwardly bowing or "peaking" of the surface by opposing transverse pressure on its longitudinal edges during the repeated normal use of the book is obviated, particularly when the book cover is of relatively thin or soft paperboard, as will be herein-after described and claimed.

In the drawing—

Figure 1 is a perspective view of a book of matches embodying my invention, the ignition material being omitted to show the transverse corrugations of the rectangular end of the cover, such corrugations being somewhat magnified for clearness.

Fig. 2 is a similar view with the ignition material applied to the corrugated surface.

Figs. 3 and 4 are partial longitudinal vertical sections, enlarged, of the books shown in Figs. 1 and 2, respectively.

Fig. 5 is a transverse vertical section, as on the line 5—5 of Fig. 4.

Fig. 6 is a sectional elevation showing roll devices for corrugating the cover material.

Fig. 7 is a transverse vertical section through the rolls, as on the line 7—7 of Fig. 6, showing in addition, means for progressively applying ignition material to the corrugated surface, and also means for pre-moistening such surface.

The form of match book illustrated in the drawing comprises one or more match cards or combs A and a flexible cover B therefor. Each card comprises a row of match stems 10 headed at their outer or free ends and frangibly attached at their inner ends to the uncut base portion 11. The cover consists of an elongated rectangular strip of flexible paperboard formed and folded to embrace the back, front and ends of the associated match cards. The front wall provides a short retaining fold 12 which, together with the lower portion of the back wall 13, merges with a flat panel 14 constituting the friction bearing end of the cover. The fold 12 and the lower portion of the wall 13 are fastened to the bases of the cards by means, for example, of a suitably disposed clenched staple 15, which staple clamps together

such fold and wall portion and imparts thereto a flaring formation effective to support and brace the longitudinal edges of the panel, as described in Patent No. 2,101,111 aforesaid.

In the improved match book herein illustrated the end panel 14 of the cover material is formed throughout its length with relatively small transverse corrugations 16, and the outer corrugated surface thus produced is coated and covered with ignition material 17 which fills the grooves or valleys of the corrugations and presents a smooth outer friction surface. The transverse corrugations reinforce the panel and the embedded ignition material, when hard, affords a multiplicity of cross braces which contribute to the transverse reinforcement and stiffening of the panel, thereby obviating liability of the outward bowing or distortion of the ignition surface through the application of opposing transverse pressure to its longitudinal edges during the normal service of the match book, as previously mentioned. Moreover, the transverse embedded portions of the ignition material effectually lock the material to the panel, and also present an efficient match striking surface should the outer face of the material become worn from extended use.

In carrying out my invention the corrugations are progressively formed in the cover material by means, comprising, preferably, correspondingly fluted rolls between the mating peripheral surfaces of which the cover material is fed, the ignition material being thereafter applied to the corrugated surface.

In Figs. 6 and 7 the mating fluted rolls 18 are shown as mounted on parallel transverse shafts 19 having meshing gears 20, one of the shafts being driven from a suitable source of power. These shafts have their bearings in a standard (or standards) 21 rising from a bed 22 which sustains the table 23 on which the sheets of cover material (C) are supported, such sheets being delivered in succession to and between the rolls. The fluted rolls 18 are formed with lateral smooth portions 24 which bear against the upper and lower surfaces of the sheet in a manner to feed 40 and prevent distortion of the body of the sheet during the corrugating operation. Rearwardly of the rolls 18 and in operative relation to the path of the corrugated surface of the cover sheet is a roll 25, or other suitable element, which applies the ignition material to the progressing corrugated portion of the sheet. The sheets thus formed and treated are subsequently subdivided into covers of proper shape and size for association with the match cards or combs.

As each sheet progresses to the rolls 18 the under side of the portion of the sheet which is to be corrugated may pass over a suitably-located steam head 26 which is supplied with steam from any suitable source, the escaping steam being directed against the opposing sheet and imparting moisture thereto.

I claim—

1. A match packet comprising card matches and a cover therefor of flexible paperboard folded about and fastened to the base of the matches to provide a flat rectangular end portion for ignition material, and flaring side portions which support

the longitudinal edges of said end portion, said end portion being transversely corrugated, and said ignition material covering the outer corrugated surface and being embedded in the grooves thereof.

2. A cover for match packets of the type described, comprising a sheet of flexible paperboard foldable transversely of the sheet to provide a flat rectangular end portion, said portion being transversely corrugated throughout its length and exteriorly coated with ignition material embedded in the grooves of the corrugations.

JOHN R. NOLAN.
